DESIGN FOR A COMBINATION SHELF BRACKET AND GARMENT HANGER

Thomas C. MacArthur, Berkeley, Calif.

Application July 24, 1939, Serial No. 86,219

Term of patent 14 years

To all whom it may concern:

Be it known that I, Thomas C. MacArthur, a citizen of the United States, residing at Berkeley, county of Alameda, in the State of California, have invented a new, original, and ornamental Design for a Combination Shelf Bracket and Garment Hanger, of which the following is a specification, reference being had to the accompanying drawing, forming a part thereof.

Fig. 1 is a front elevational view of a combination shelf bracket and garment hanger, showing my new design;

Fig. 2 is a top plan view thereof;
Fig. 3 is an end view thereof; and
Fig. 4 is a perspective view.

I claim:

The ornamental design for a combination shelf bracket and garment hanger, as shown.

THOMAS C. MACARTHUR.
